UNITED STATES PATENT OFFICE.

ROBERT PARKS, OF McDONALD, PENNSYLVANIA.

PAPER-HANGING DEVICE.

Application filed August 31, 1925. Serial No. 53,676.

To all whom it may concern:

Be it known that I, ROBERT PARKS, a citizen of the United States, residing at McDonald, in the county of Washington and State of Pennsylvania, have invented certain new and useful Improvements in a Paper-Hanging Device, of which the following is a specification.

This invention relates to an improved device to be used by paper hangers, and other persons for affixing wall paper to a wall.

The invention has more particular reference to a portable contrivance including a part on which the strip of paper is laid in a folded state, together with a guide and pressure roller over which the paper passes to permit the pasted side to be pressed against the wall to adhere thereto.

The particular details and their relative association will become more readily apparent from the following description and drawing.

In the accompanying drawing forming part of this application, and in which like numerals are employed to designate like parts throughout the same:

Figure 1 is an end view of a paper hanger device constructed in accordance with the invention.

Figure 2 is a side view of the same showing the approximate manner in which the wall paper is associated therewith while being applied.

Figure 3 is a top plan view with a portion of the pressure roller broken away to disclose the construction more plainly.

Referring to the drawing in detail, the reference character 1 designates a handle composed of separable and adjustable sections 2 and 3, coupled or otherwise connected together at 4. At the upper end of the upper handle section 2 is a substantially rectangular frame 5. This frame is connected to the handle by the downwardly converging arms 45 or portions 6, and the central socket 7. A roller 8 of rubber or other comparatively soft material is journaled for rotation on the upper horizontal bar of the frame 5. There is a small right angular bracket 9 on one of the end bars of the frame, and this bracket is provided with a set screw which serves the purpose to be hereinafter made clear.

Extending normally at right angles from the frame 5 is a vertically swingable shelf 10 in the form of an open work frame. It is

preferably made up of a plurality of slats connected together in the approximate order shown in Figure 3. This shelf is provided with bearing brackets 11 which are journaled for rotation on the lower horizontal bar of the aforesaid frame 5. The shelf is equipped with the pivoted arcuate arm 12, the free end portion of which extends through the bracket 9 and is held in various adjusted positions by the set screw carried by this bracket. Adjustably mounted on the shelf 10 is a slidably mounted bar 12^a which is equipped with a plurality of fingers or hooks 13.

In using the improved device, a strip of paper of the desired length is cut and the paste applied thereto in the customary way. Then the paper is folded somewhat in the manner indicated in dotted lines in Figure 2, after which it is laid upon the upper side of the shelf 10. The shelf is then in substantially the horizontal position shown, being held in this position by the retainer arm 12 and the bracket 9. The slide 12^a is adjusted 80 according to the width of the paper to facilitate unfolding. The free end portion of the paper is then passed over the pressure roller 8, and is attached to the side wall and ceiling in one corner in a customary manner. After the paper is started, it is obvious that by taking hold of the handle and walking across the room, the strip of paper may be pressed against the ceiling by holding the roller up and against the paper. As the paper is thus rolled on, it is also unfolded from the shelf, and when the opposite side of the room is reached, the shelf may be let down to assume a perpendicular position. In this way, the shelf will not interfere with the complete application of the strip of paper from one side wall to the opposite wall. The handle may be made extensible so that the paper may be applied by walking across the floor, or it may be of any length 90 so that in case a scaffold is provided, the device may be conveniently used. It is obvious that the device is not restricted to applying ceiling paper only, but may be used equally well on applying side wall paper.

The features and advantages of the device of this class are doubtless clear. Moreover, the construction will be understood from a careful reading of the description in connection with the drawings. Therefore, a more lengthy description is deemed unnecessary.

While the preferred embodiment of the invention has been shown and described, it is to be understood that minor changes coming within the field of invention claimed 5 may be resorted to if desired.

Having thus described the invention, what I claim is:—

1. In a paper hanging device of the class described, a support having a frame at its 10 top, a roller mounted for rotation on said frame, a shelf pivotally mounted on said frame, and a slide carried by said shelf.
2. In a paper hanging device of the class described, a portable support, a presser roll 15 carried thereby, a paper supporting shelf pivotally mounted on the support, a bar slidable on the shelf, and paper engaging hooks carried thereby.
3. In a paper hanging device, the combination with a handle, of a substantially rectangular shaped frame supported vertically on the upper end of the handle, a pressing roller journaled for rotation on the upper horizontal bar of said frame, a substantially 20 rectangular shaped shelf member pivotally mounted on the lower horizontal bar of said frame, a bracket secured on one of the ends of the vertical frame, an arcuated shaped arm pivotally connected at one end to one side of said shelf, the free end of said arcuate arm extending through said bracket, and a set screw associated with the bracket and 25 cooperating with the arcuate arm for maintaining the pivoted shelf in any adjusted position.

mounted on the lower horizontal bar of said frame, an elongated bar adapted for slidable movement across the shelf, and paper engaging fingers extending upwardly from the bar.

4. In a paper hanging device, the combination with a handle, of a substantially rectangular shaped frame supported vertically on the upper end of the handle, a pressing roller journaled for rotation on the upper horizontal bar of said frame, a substantially rectangular shaped shelf member pivotally mounted on the lower horizontal bar of said frame, a bracket secured on one of the ends of the vertical frame, an arcuated shaped arm pivotally connected at one end to one side of said shelf, the free end of said arcuate arm extending through said bracket, and a set screw associated with the bracket and 40 cooperating with the arcuate arm for maintaining the pivoted shelf in any adjusted position.

In testimony whereof I affix my signature.

ROBERT PARKS.
